Primary Examiner — Catherine Ho*Assistant Examiner* — Tyenne A. Fulton-Crosson(74) *Attorney, Agent, or Firm* — Tucker Ellis LLP(57) **CLAIM**

The ornamental design for an armchair, as shown and described.

DESCRIPTION

FIG. 1 is a front, left side, top perspective view of an armchair embodying my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is bottom view thereof.

The broken lines are for the purpose of illustrating portions of the armchair and form no part of the claimed design.

1 Claim, 7 Drawing Sheets(56)
